MACHINE FOR SELECTING AND SPOOLING
YARNS FOR AXMINSTER LOOMSRalph W. Homan, Bloomsburg, Pa., assignor to
The Magee Carpet Company, Bloomsburg, Pa., a
corporation of Pennsylvania

Application July 30, 1936, Serial No. 93,498

51 Claims. (Cl. 28—55.5)

This invention relates to machines for selecting and spooling yarns for Axminster looms and more particularly to improvements in the construction and operation of the machine disclosed in my prior Patent Number 1,928,724 granted to me on October 3, 1933.

It is an object of the present invention to simplify the construction of the machine, improve its operation to insure accuracy in the selection of the desired colored yarns and lessen the cost of manufacture.

A further object resides in providing means for moving the individual yarn carriers longitudinally of their supporting tracks including electrically operated means for controlling the release of the individual yarn carriers from the moving means.

A still further object resides in providing electrical mechanism for the automatic selection of the desired colored yarns including mechanism controlled by a perforated pattern sheet for controlling the operation of the electrical mechanism.

Another object of the invention resides in providing warp clamping means for releasably holding the ends of the yarns extending from the carriers during the selecting operation and means for collecting the selected yarns and drawing them into close parallel relation for attachment to the warp beam winding machine.

In carrying out my invention, I provide a series of horizontal rows of yarn carriers slidably mounted on tracks, each row carrying a series of different colored yarns supplied from a suitable creel; mechanism for moving the individual carriers along the tracks; electrically controlled mechanism for releasing the individual carriers from the moving means; mechanism operated by a perforated pattern sheet for controlling the electrical mechanism to automatically select the desired colored yarns in accordance with the pattern; means for holding the loose ends of the yarns during the selecting operation and means for collecting the selected yarns in proper relation for attachment to a warp beam winding machine.

Other objects and advantages of the invention will be apparent during the course of the following description.

In the drawings, forming a part of this specification and in which like numerals are employed to designate like parts throughout the same,

Figs. 1 and 1a, taken together, are a side elevation of the selector machine in its entirety, together with the warp clamp, warp beam winder and creel.

Figs. 2 and 2a are a rear elevation of the selector machine,

Fig. 3 is an enlarged view of the yarn carrier release mechanism,

Fig. 4 is a fragmentary perspective view of the 5 warp clamping member,

Fig. 5 is an enlarged detail side elevation of the circuit closing and opening mechanism for controlling the yarn carrier release mechanism,

Fig. 6 is a detail sectional view taken on line 10 6—6 of Fig. 5,

Fig. 7 is a fragmentary perspective view of one of the tracks and yarn carriers thereon.

Fig. 8 is a longitudinal sectional view of one 15 of the yarn carriers,

Fig. 9 is a top plan view of the yarn collecting comb and supporting frame therefor,

Fig. 10 is an enlarged section taken on line 10—10 of Fig. 9, and,

Fig. 11 is a section taken on line 11—11 of 20 Fig. 9.

In the drawings, wherein for the purpose of illustration, I have shown a preferred embodiment of the invention, the letter A denotes a creel for holding the general supply of yarns, 25 B the selector machine and C the warp beam winding machine. The frame of the selector machine consists of vertical standards 6 and 7 connected at their upper and lower ends by cross beams 8 and 9. Extending longitudinally of the 30 frame are a series of horizontal tracks 10 arranged in vertical spaced superimposed relation, each track consisting of a pair of spaced parallel rods 11 connected at their ends to the standards of the frame by nuts 12. A series of individual 35 yarn carriers 13 are slidably mounted on the tracks 10, each carrier consisting of an elongated block having transverse openings 14 therethrough for the passage of the rods 11 on which the carriers slide. A tubular sleeve 15, through which 40 the yarn 16 extends, is secured to the upper edge of the block and extends the length thereof. Each horizontal row of carriers support yarns of the same color while the vertical rows are made up of yarns of different colors. The number of 45 yarns in each horizontal row will vary according to the pattern of the carpet or rug for which the yarns are to be selected. The general supply of yarns for the carriers is provided from the creel A. The creel is preferably of a type which 50 will permit free unwinding of the yarns from the cheeses, with friction driving means for rotating the cheeses in a reverse direction to take up the slack in the yarns when desired.

The carriers 13 are moved along the tracks 10 55

by rotatable shafts 17 extending from the vertical plate 18 which is provided with openings 19 for the passage of the rods 11 therethrough, to permit sliding movement of the plate along the tracks. 5 The upper and lower ends of the plate 18 have screw threaded blocks 19 and 20 to receive the screw shafts 21 and 22 at the top and bottom of the selector frame. The shafts 21 and 22 have one end mounted in bearings in the standard 6 10 while their opposite ends are journaled in bearings 23 and 24 attached to the upper and lower cross beams of the frame. The rotatable shafts 17 extend longitudinally of the tracks 10 intermediate the rods 11 and each of the carriers 13 15 is provided with a central opening 25 through which the shaft 17 is adapted to extend. The carriers are retained on the free end of the shafts 17 by a pin 26 extending transversely through the shafts, the opening 25 being provided with 20 opposed notches 27 to permit separation of the individual carriers from the shafts 17 when the shafts are rotated to bring the pin 26 in register with the notches. The carriers on one side are provided with recesses 28 surrounding the openings 25 which permit free oscillation of the shafts 17 and pins 26 after release of the individual carriers. A stop block 29 slidably mounted on the track and shaft holds the series of carriers close together and an adjustable sleeve 30 mounted 25 on the shaft holds the block in position. The inner end of the shafts 17 project through and extend slightly beyond the plate 18 having pinions 31 fixedly mounted thereon which mesh with the rack bars 32 extending transversely of the 30 plate 18. The rack bars at one end are supported by guide brackets 33 and at their opposite ends are connected through links 34 to the core 35 of a solenoid magnet 36. When the magnets are energized the rack bars are moved to turn the shafts 17 a quarter of a turn to align the pins 26 at the end of the shafts with the notches 27 of the openings 25 through the carriers, thereby permitting the end carrier on the shaft to be detached therefrom. Upon release of the end carrier from the shafts 17 its movement is arrested 35 by means of the spring wire 37 extending longitudinally of the bottom edge of the carrier and attached thereto intermediate its length. The ends of the wire 37 are freely movable in the 40 vertical slots 38 in the ends of the carriers, which intersect the openings 14 and by reason of their resiliency frictionally engage the rods 11 holding the carrier at the point on the track where released. When the solenoid magnets are de-energized the rack bars 32 are moved in the opposite direction by the coil springs 39 attached at one end to a pin 40 carried by the rack bars and at their opposite end to a pin 41 carried by the 45 guide plate 42 disposed above the rack bars. The free ends of the rack bars 32 project slightly beyond the edge of the plate 18 and are adapted to be engaged by the bar 43 supported by brackets 44 attached to the plate 18. The bar 43 is mounted for movement in a direction towards and away from the ends of the rack bars, being 50 operated by a manually actuated lever 44' which actuates a rod 45 having arms 46 in engagement with the bar 43 which move the bar towards the ends of the rack bars, to simultaneously move all the rack bars in a direction to rotate the shafts 17, so that the pins 26 align with the notches 27, permitting the shafts to freely pass through the 55 openings 25 of the carriers released upon the 60 tracks, when the machine is being returned to a 65 starting position.

The lever 44' is normally held in an inoperative position by the spring 47.

An automatic circuit closing and opening mechanism is provided for controlling the energizing of the magnets 36 and includes a stand 48 having mounted thereon an insulation contact block 49 supported by arms 50 pivotally mounted on the frame members 51 by pivot pins 52. Contact strips 53 of suitable conducting metal are positioned on top of the block 49 in parallel spaced relation, there being one contact strip for each of the magnets and one for the magnetic clutch 54. An adjusting screw 55 engages the rear ends of the arms 50 for regulating the pivotal movement of the contact block and beneath the forward end of the block, at each corner, are coil springs 56 which cushion the downward movement of the block and returns the same to its normal position. A roller 57 is mounted forward of the contact block having a series of spaced longitudinal grooves 58 in its periphery and at each end sprocket teeth 59. A pattern sheet 60 is trained over the roller having perforations along its edge which engage the sprocket teeth 59, whereby the pattern sheet is caused to move over the roller upon rotation thereof. The pattern sheet is fed to the machine from a spool 61 mounted at the forward end of the stand and is rewound on a driven spool 62 at the rear end of the stand. The pattern sheet 60 has openings 63 punched therethrough which align with the grooves 58 as the pattern moves over the roller 57. A series of trip levers 64 are supported above the roller 57 in a guide comb 65 and mounted in the outer ends of the levers 64 are pins 66 which move over the surface of the pattern. A spring 67 normally urges the pins 66 in a downward direction so that when the openings 63 align with the pins, the pins are forced downwardly into engagement with the groove of the roller, whereby the trip lever 64 is caused to move in the direction of rotation of the roller. The inner ends 68 of the trip levers 64 are circular shape and fit in correspondingly shaped sockets 69 of the hanger plates 70 which are disposed vertically in a guide frame 71, the upper ends being bifurcated, as at 72, to engage a guide rod 73 while the lower end bears against the lower member of the frame 71. The individual hanger plates 70 are normally held in a raised inoperative position by springs 74 mounted on the bar 75 which engage the lip 76 formed on the edge of the hanger plates. A rocker arm 77 is mounted on a rocker shaft 78 above the contact block and at its forward end carries a plate 79 adjustable by means of a screw 80. A shoulder 81 is formed on the rear edge of the hanger plates 70 and when the hanger is moved inwardly through the action of the trip lever, the shoulder is disposed in the path of movement of the rocker arm plate 79 which strikes the shoulder and causes the hanger plate to move downwardly, so that the lip 76 engages with the contact strip 53 to close the electric circuit of one of the magnets. The wires 82 leading from the contact strips 53 have plugs 83 at their ends for detachable engagement with the sockets 84 in a switch panel 85 and wires 86 leading to the magnets from the sockets are housed within a flexible conduit 87. The plugs 83 permit ready interchanging between the circuits of the individual magnets, so that a change or alteration may be made in the pattern being selected without the necessity of punching a new pattern sheet. To facilitate changing of the circuits, numbers are applied to the plugs 83 and 75

sockets 84 which correspond to the numbers on the ends of the stop blocks 29 of each horizontal row of carriers.

A warp clamping member for holding the loose ends of the yarns during the selecting operation is positioned forward of the selector frame being mounted to move in a direction longitudinally thereof. All the yarns extending from the carriers are held by the warp clamp at the beginning of the selection operation and after the carriers have been selected for a particular line, the yarns of the selected carriers are removed from the warp clamp and clamped in the winder beam C. The unselected yarns are retained in the clamp member and thereby held separate from the selected yarns. The clamp consists of a vertical angle bar 88 having screw blocks 89 at its upper and lower ends which travel on the screw shafts 90 extending longitudinally of the selector frame. The screw shafts are journaled in bearings 91 mounted on the vertical posts 92, positioned in a line at a slight angle to the selector frame so that as the clamp moves across the frame it is brought nearer to the frame. A sprocket wheel 93 is mounted on one end of each shaft and an endless chain 94 connects the sprocket wheels of the shafts so that they turn in unison. Attached to one edge of the angle bar 88 is a comb 95 through which the yarns are inserted and to one side of the comb is a rotary wire brush member 96 for receiving and holding the ends of the yarns drawn through the comb. The ends of the member 96 are fastened to the bar 88 by bolts 97.

The mechanism for collecting the yarns which have been selected by the selector machine consists of a fan shaped comb 98 composed of a series of flat metal teeth 99, disposed in spaced parallel relation and connected at one end to a bar 100. The teeth of the comb at their outer free ends are spaced farther apart than at their inner ends, the intermediate portion of the teeth being bent at an angle to direct the yarns entering the teeth at their outer ends towards the inner ends of the teeth, thus drawing the yarns into closer relation. The comb 98 is supported in a horizontal plane by a rectangular frame 101 suspended on a horizontal plane in front of the selector machine by vertical rack bars 102 extending through the upper cross beam 8 and mounted in suitable guideways attached to the frame of the selector. The rack bars 102 mesh with gears on the shaft 103 mounted on top of the beam 8 which is driven by a reversible electric motor 104. The bar 100 rests loosely on the rear longitudinal member 104 of the frame 101, while the forward ends of the teeth of the comb are disposed in guide slots 105 formed in the top of the front longitudinal member 105 of the frame 101. The teeth are held in the slots by a bar 106 removably held on top of the teeth by pins 107 projecting upwardly from the frame 101, which engage in openings in the ends of the bar. The forward ends of the teeth 99 project beyond the frame 101 and as the comb moves downwardly past the front of the selected carriers the yarns are collected between the teeth. Upon reaching the bottom, the bar 106 is removed and the bar 100 is swung upwardly towards the selector machine to dispose the comb in a vertical plane. The frame 101 is then returned to its original position at the top of the selector frame and then the comb is drawn along the selected yarns towards the warp beam winding machine C, during which operation the yarns move towards the inner ends of the comb teeth, into closer spaced relation for attachment to the

warp beam of the winding machine. The comb containing the selected yarns is supported on the front of the warp beam winder by suitable brackets and guides the yarns during the winding operation.

The driving mechanism includes a reversible electric motor 108 supported by a frame 109 adjacent the stand 48 and standard 6. One end of the motor shaft 110 is equipped with a worm 111 which meshes with a worm wheel 112 mounted on the end of the screw shaft 22 projecting beyond the standard 6. A sprocket wheel 113 is also fixed on the screw shaft 22 and is connected with the sprocket wheel 114 fixed on the screw shaft 21 by an endless chain 115, whereby the screw shafts 15 are rotated in unison to move the plate 18 longitudinally of the selector frame. A gear wheel 116 mounted on shaft 21, through an intermediate gear 117, drives the gear 118 fixed on the horizontal shaft 119 mounted in a bearing 120 attached to the standard 6. The shaft 119 carries a bevel gear 121 which meshes with the bevel gear 122 at the upper end of the vertical shaft 123 mounted in bearings 124 attached to the standard 6. A bevel gear 125 is attached to the lower end of the vertical shaft 123 and meshes with a bevel gear 126 on the end of the drive shaft 127 which through a worm 128 drives the worm gear 129 on the end of the shaft of the roller 57, whereby the roller is rotated to feed the pattern sheet 60. A pulley 130 on the drive shaft 127 is connected by an endless belt 131 with the pulley 132 on the shaft of the spool 62 for rewinding the pattern sheet on the spool. A rocker arm 133 connected to the end of the rocker shaft 18 is actuated by a cam 134 mounted on the shaft 127. The magnetic clutch 54 is interposed in the shaft 127 for automatically controlling the drive shaft, the electric circuit of the magnetic clutch being controlled by one of the contact strips 53 of the automatic circuit closing and opening machine. The gear wheel 116 also meshes with an intermediate gear 136 which drives the gear 137 mounted on shaft 138. The shaft 138 is connected by a universal joint 139 to the shaft 140, which through the universal joint 141 connects with the upper screw shaft 98 of the warp clamping member. A magnetic brake 142 is mounted on the free end of the motor shaft 110 which connects with the circuits of the motor 108 and is brought into operation upon breaking of the circuits to stop the motor. Various manual and automatic switches are interposed in the circuits for stopping and starting the motors 108 and 104.

In operation, the yarns 16 are supplied from the creel A, the individual yarns being drawn through the tubular sleeves 15 of the individual yarn carriers 13 mounted on the horizontal tracks 10 of the selector machine. The carriers of each track will carry yarns of the same color and the number of tracks employed in the selection of the yarns will depend on the number of colors in the pattern of the carpet or rug for which the yarns are to be selected.

After the carriers are supplied with the desired colored yarns, the loose ends of the yarns projecting from the carriers are secured in the warp clamping member and the machine is ready to operate. The motor 108 is started and through gearing drives the screw shafts 21 and 22 which cause the plate 18 to move longitudinally of the tracks 10. At the same time the motor drives the shaft 127 which rotates the roller 57 of the circuit opening and closing machine and also imparts movement to the rocker shaft 18. As the

pattern sheet 60 moves over the roller, the pins of the individual trip levers 64, successively drop through the openings punched in the sheet and engage in the grooves of the roller, whereby the 5 trip levers are moved to swing the hanger plates 70 to bring the shoulder 81 of the hanger plate into the path of movement of the rocker arm plate 78 which is constantly reciprocated by the rocker shaft 78. The rocker arm plate 78 upon 10 engaging the shoulder 81 forces the hanger plate downwardly so that the lip 78 engages the contact strip 53 to close the circuit of the magnets 38 which are supported by and move with the plate 15 18. Upon energizing the magnets 38, the rack bars 32 are moved to rotate the shafts 17 which extend through the openings 25 of the yarn carriers, so that the pins 26 are aligned with the notches 27 of the openings, thereby releasing the outermost carriers on the shafts. The carriers 20 when released are held in position on the tracks by the spring wires 37 which frictionally engage the rods of the tracks. The circuits of the magnets are only momentarily closed and upon de-energizing of the magnets, the rack bars are 25 moved by the springs 38 to rotate the shafts 17 in a reverse direction so that the pins 26 are moved out of alignment with the notches 27 locking the remaining carriers on the shafts. Thus, it is seen the pattern sheet 60 automatically controls 30 the opening and closing of the magnet circuits and the magnets control the release of the carriers from the shafts 17, as the carriers are moved along the tracks.

During the selecting operation, the warp 35 clamping member holding the loose ends of the yarns is moved longitudinally of the selector frame in unison with the carrier moving means and when the selecting operation for the particular line is completed, the selected yarns are 40 moved from the clamping member and the unselected yarns are retained by the clamp in separate relation to the selected yarns.

On completion of the selection of the desired 45 yarns the motor is stopped and the selected yarns are permitted to hang downwardly in vertical relation to the selector frame. The motor 104 which drives the yarn collecting mechanism is then started and the collector comb 98 is lowered past the front ends of the selected yarn carriers, 50 so that the yarns hanging therefrom are collected between the forward ends of the comb teeth. When the comb reaches the bottom it is manually lifted off the frame 101 and swung to a vertical plane, at which time the motor 104 is reversed to 55 return the frame 101 to its uppermost position. The comb 98 is then drawn along the yarns so that the yarns are caused to move towards the inner ends of the comb teeth which are spaced closer together, thereby drawing the yarns closer 60 together and in proper relation for attachment to the warp beam of the winding machine C. After winding the selected yarns on the warp beam, the operation of selecting the yarns is completed and the motor 104 is started in reverse to 65 drive the shafts 21 and 22 to return the plate 18 to its starting position. At this time, the bar 43, through operation of the lever 44', is actuated to move all the rack bars 32 in a direction to rotate the shafts 17 to bring the pins 26 in alignment with the notches 27 of the openings 25 of 70 the carriers, so that as the plate 18 returns to its starting position, the shafts 17 pass through the openings of the yarn carriers distributed along the tracks, automatically collecting the carriers 75 for the next operation of the machine.

It is to be understood that the form of my invention herewith shown and described is to be taken as a preferred example of the same and that certain changes in the shape, size and arrangement of the parts may be made without departing from the spirit of the invention or the scope of the subjoined claims.

Having thus described my invention, I claim:

1. A machine of the character described including a series of tracks, individual yarn carriers 10 slidably mounted on said tracks, means for moving said carriers along said tracks releasably connected with said carriers, and means for positively operating said last mentioned means to release said carriers therefrom.

2. In a machine of the character described, means to support a complement of yarns in vertically spaced horizontal tiers, releasable means for moving said yarns longitudinally of said tiers, and automatic means for positively 20 operating said moving means to successively release individual yarns in each tier from said moving means.

3. In a machine of the character described, means to support a complement of yarns in 25 vertically spaced horizontal tiers, releasable means for moving said yarns longitudinally of said tiers and means for positively operating said last mentioned means to release said yarns successively.

4. In a machine of the character described, including a series of vertically spaced horizontal tracks, individual yarn carriers slidably mounted on said tracks, shafts for moving said yarn carriers along said tracks and means for operating 35 said shafts to successively release said carriers from said shafts.

5. In a machine of the character described including a series of horizontal tiers of independently movable individual yarn carriers, releasable 40 means for connecting the yarn carriers of each tier together and moving them along the tiers, means for positively operating said last mentioned means to release said yarn carriers and means for holding said yarn carriers in released 45 position.

6. In a machine of the character described, including a series of horizontal tiers of independently movable individual yarn carriers, shafts for moving said yarn carriers along said tiers, means 50 carried by said shafts releasably holding said yarn carriers together and means for operating said shafts to release said yarn carriers successively from said shafts.

7. In a machine of the character described, including a series of horizontal tiers of independently movable individual yarn carriers, means for pulling said yarn carriers along said tiers releasably connected therewith, mechanism for positively operating said pulling means to release 60 the pulling means from engagement with said yarn carriers, and a record sheet for controlling said mechanism.

8. In a machine of the character described including a series of horizontal tiers of independently movable individual yarn carriers, means for pulling said yarn carriers along said tiers releasably connected therewith, means for positively operating said pulling means to release 65 said yarn carriers therefrom, electrical means for actuating said operating means and automatic mechanism for controlling said electrical means to successively release said yarn carriers.

9. In a machine of the character described including a series of horizontal tiers of independ- 75

ently movable individual yarn carriers, means for pulling said yarn carriers along said tiers releasably connected therewith, electrical means for positively actuating said pulling means to successively release said yarn carriers therefrom, a circuit making and breaking mechanism for controlling said electrical means, and a record sheet for controlling said circuit making and breaking mechanism.

10. In a machine of the character described including a series of horizontal tracks, a series of individual yarn carriers slidably mounted on said tracks, rotatable shafts extending through said carriers having releasable means for holding said carriers thereon, means for moving said shafts longitudinally of said tracks, electrical means for rotating said shafts to release said carriers therefrom, means for holding said carriers in released position on said tracks, circuit making and breaking mechanism for controlling said electrical means, and a record sheet for controlling said circuit making and breaking mechanism.

11. In a machine of the character described including a series of horizontal tracks, a series of individual yarn carriers slidably mounted on said tracks, means for pulling said carriers along said tracks releasably connected thereto, means for operating said pulling means to successively release said carriers and a yarn collecting comb movable downwardly past the ends of the released carriers for collecting the selected yarns.

12. In a machine of the character described including a series of horizontal tiers of independently movable individual yarn carriers, means for moving said yarn carriers along said tiers, means for selecting the individual yarns and a yarn collecting member movable downwardly past the end of the selected yarn carriers including a removable comb for gathering the selected yarns and transporting them to a warp beam winder.

13. In a machine of the character described including a series of horizontal tiers of independently movable individual yarn carriers, means for moving said yarn carriers along said tiers, means for selecting the individual yarns and a yarn collecting member movable downwardly past the ends of the selected yarn carriers including a removable fan shaped comb for gathering and drawing the selected yarns into close parallel relation and transporting them to a warp beam winder.

14. In a machine of the character described including a series of horizontal tiers of independently movable individual yarn carriers, means for moving said yarn carriers along said tiers, means for selecting the individual yarns and a warp clamping member movable across the front of said tiers for receiving and holding the ends of the yarns.

15. In a machine of the character described including a series of horizontal tiers of independently movable individual yarn carriers, means for moving said yarn carriers along said tiers, means for selecting the individual yarns, a warp clamping member movable across the front of said tiers for receiving and holding the ends of the yarns and a collecting comb movable downwardly past the ends of the selected yarns for collecting and drawing the yarns to a common plane.

16. A machine of the character described including a series of tracks, a series of individual yarn carriers slidably mounted on said tracks,

means yieldably holding said carriers on said tracks, means for pulling said carriers along said tracks releasably connected thereto and means for actuating said pulling means to successively release said carriers.

17. A machine of the character described comprising a series of tracks, a series of individual yarn carriers movably mounted on said tracks, reciprocating oscillatable shafts for moving said carriers along said tracks and means connecting said shafts with said carriers for releasing said carriers from said shafts upon oscillation of the shafts.

18. A machine of the character described including a series of tracks, a series of individual yarn carriers movably mounted on said tracks, reciprocating oscillatable shafts for moving said carriers along said tracks, means carried by said shafts detachably connecting said carriers with said shafts adapted to release said carriers upon oscillation of said shafts and means for oscillating said shafts.

19. A machine of the character described including a series of tracks, a series of individual yarn carriers movably mounted on said tracks, reciprocating oscillatable shafts for moving said carriers along said tracks, means carried by said shafts releasably connecting said yarn carriers with said shafts and means for oscillating said shafts to release said yarn carriers successively from the shafts.

20. A machine of the character described including a series of tracks, a series of individual yarn carriers movably mounted on said tracks, spring friction means normally holding said yarn carriers stationary on said tracks and means operable to move said yarn carriers along said tracks and successively release said yarn carriers.

21. A machine of the character described including a series of tracks, individual yarn carriers movably mounted on said tracks, reciprocating oscillatable shafts extending through said yarn carriers for moving the carriers along said tracks and means releasably holding said yarn carriers on said shafts operable to release said yarn carriers upon oscillation of said shafts.

22. A machine of the character described including a series of tracks, individual yarn carriers movably mounted on said tracks, shafts extending through said yarn carriers, means releasably holding said yarn carriers on said shafts, means for moving said shafts longitudinally of said tracks and means for rotating said shafts to release said yarn carriers from said shafts.

23. A machine of the character described including a series of tracks, individual yarn carriers movably mounted on said tracks, shafts extending through said yarn carriers, means releasably holding said yarn carriers on said shafts, friction means normally holding said yarn carriers stationary on said tracks, means for moving said shafts longitudinally of said tracks to move said yarn carriers along the tracks, and means for rotating said shafts to release said yarn carriers from the shafts.

24. A machine of the character described including a series of tracks, a series of individual yarn carriers movably mounted on said tracks, reciprocating oscillatable shafts releasably connected with said yarn carriers for moving the carriers along said tracks and electro-magnets for oscillating said shafts to release said yarn carriers when the carriers are moved along said tracks.

25. A machine of the character described including a series of tracks, a series of individual yarn carriers movably mounted on said tracks, rotatable shafts releasably connected with said 5 yarn carriers, means for moving said shafts longitudinally to move said yarn carriers along said tracks, and means carried by said moving means for rotating said shafts to release said yarn carriers therefrom.
- 10 26. A machine of the character described including a series of tracks, a series of individual yarn carriers movably mounted on said tracks, rotatable shafts releasably connected with said 10 yarn carriers, means for moving said shafts longitudinally to move said yarn carriers along said tracks and electro-magnets carried by said moving means for rotating said shafts to release said 15 yarn carriers therefrom.
- 15 27. A machine of the character described including a series of tracks, a series of individual 20 yarn carriers movably mounted on said tracks, reciprocating oscillatable shafts releasably connected with said yarn carriers for moving the carriers along said tracks, pinion gears fixed on said shafts, a rack meshing with said gears and means for reciprocating said racks to oscillate 25 said shafts for releasing said yarn carriers from the shafts.
- 20 28. A machine of the character described including a series of tracks, a series of yarn carriers movably mounted on said tracks, spring 30 friction means carried by said yarn carriers engageable with said tracks to normally hold said carriers stationary, and means for moving said carriers along said tracks.
- 25 29. A machine of the character described including a series of tracks, a series of yarn carriers movably mounted on said tracks, spring 35 wires mounted in said yarn carriers having frictional contact with said tracks to normally hold said yarn carriers stationary and means for moving said carriers along said tracks.
- 30 30. A machine of the character described including a series of tracks, each track being composed of spaced parallel rods, a series of yarn carriers having spaced transverse openings to receive said rods on which the carriers are adapted to slide, means disposed intermediate said rods 40 detachably connecting said yarn carriers together for moving the carriers along said tracks.
- 35 31. A machine of the character described including a series of tracks, each track being composed of spaced parallel rods, a series of yarn carriers having spaced transverse openings to receive said rods on which the carriers are adapted to slide, said carriers having slots intersecting the openings through the carriers, spring means disposed in said slots adapted to frictionally contact said rods to normally hold said carriers 45 stationary and means releasably connecting said carriers together for moving said carriers along said tracks.
- 40 32. A machine of the character described including a series of tracks, a series of yarn carriers 50 movable along said tracks, shafts extending through openings in said carriers, pins extending radially from said shafts adapted at times to register with notches extending from the openings of the carriers through which the shafts extend, means for moving said shafts longitudinally of said tracks and means for rotating said shafts 55 to move said pins into and out of register with said notches.
- 45 33. In a machine of the character described, 60 including a series of horizontal tiers of independently movable individual yarn carriers, means for moving said yarn carriers along said tiers, means for selecting the individual yarns, a warp clamping member extending vertically of said tiers, and means for moving said clamping member longitudinally of said tiers.
- 50 34. In a machine of the character described including a series of horizontal tiers of independently movable individual yarn carriers, means for moving said yarn carriers along said tiers releasably connected therewith, electrical operating 65 means for releasing said carriers from said moving means, and selective circuit breaking and making mechanism for controlling said electrical operating means.
- 55 35. In a machine of the character described including a series of horizontal tiers of independently movable individual yarn carriers, means for moving said yarn carriers along said tiers operable to successively release the yarn carriers along said tiers, electro-magnets for operating said moving means to release said yarn carriers, 70 and selective circuit making and breaking mechanism for controlling said electro-magnets.
- 60 36. In a machine of the character described including a series of horizontal tiers of independently movable individual yarn carriers, means for moving said yarn carriers along said tiers operable to successively release the yarn carriers along said tiers, electro-magnets for operating said moving means to release said yarn carriers, a circuit making and breaking mechanism for 75 controlling said electro-magnets and a record sheet for controlling said circuit making and breaking mechanism.
- 65 37. A machine of the character described including a series of tracks, a series of individual 80 yarn carriers movably mounted on said tracks, rotatable shafts releasably connected with said yarn carriers, means for moving said shafts longitudinally to move said yarn carriers along said tracks, electro-magnets carried by said moving means for rotating said shafts to release said 85 yarn carriers therefrom, a circuit making and breaking mechanism for controlling said electro-magnets and a record sheet for controlling said circuit making and breaking mechanism.
- 70 38. In a machine of the character described including a series of horizontal tiers of independently movable individual yarn carriers, means for moving said yarn carriers along said tiers, means for selecting the individual yarns, a warp clamping member extending vertically of said tiers, and means for moving said clamping member 90 longitudinally of said tiers.
- 75 39. In a machine of the character described including a series of horizontal tiers of independently movable individual yarn carriers, means for moving said yarn carriers along said tiers, means for selecting the individual yarns, a warp clamping member extending vertically of said tiers and means for supporting and moving said 95 clamping member across the front of said tiers at an angle thereto.
- 80 40. In a machine of the character described including a series of horizontal tiers of independently movable individual yarn carriers, means for moving said yarn carriers along said tiers, means for selecting the individual yarns, a warp clamping member movable across the front of said tiers for holding the ends of the 100 yarns and means for moving said clamping mem- 95

ber in unison with said carrier moving means.

41. In a machine of the character described including a series of horizontal tiers of independently movable individual yarn carriers, means for moving said yarn carriers along said tiers, means for selecting the individual yarns and a warp clamping member movable across the front of said tier including a comb and a brush.

42. The combination with a yarn selecting mechanism of a warp clamping member movable past the ends of the yarns being selected including a comb and brush for holding the yarn ends.

43. The combination with a yarn selecting mechanism of a yarn collecting member movable past the ends of the selected yarns including a fan shaped comb for gathering and drawing the selected yarns into close parallel relation.

44. In a machine of the character described, means to support a complement of yarns in superposed horizontal tiers, yarn selecting means and a comb movable downwardly past the ends of the selected yarns having teeth to receive and collect the selected yarns.

45. In a machine of the character described, means to support a complement of yarns in superposed horizontal tiers, yarn selecting means, a comb disposed on a horizontal plane and movable past the ends of the selected yarns having teeth to receive and collect the selected yarns, the inner ends of said teeth being closer together than the outer ends.

46. In a machine of the character described, means to support a complement of yarns in superposed horizontal tiers, yarn selecting means, a frame movable vertically of said tiers past the ends of the selected yarns and a yarn collecting comb removably mounted on said frame for collecting the ends of the selected yarns.

47. In a machine of the character described including a series of horizontal tiers of independently movable individual yarn carriers, means for moving said yarn carriers along said tiers, means for selecting the individual yarns, a warp clamping member to hold the ends of the yarns, means for supporting and moving said clamping member across the front of said tiers in unison with said carriers' moving means, and a

collecting comb movable vertically past the ends of the selected yarns for collecting and drawing the yarns to a common plane.

48. In a machine of the character described, including a series of horizontal tiers of independently movable individual yarn carriers, means for moving said yarn carriers along said tiers releasably connected therewith, selective mechanism for operating said moving means to successively release said carriers therefrom, and means for operating the moving means for interconnection engagement with the released yarn carriers upon return of said moving means to a starting position.

49. In a machine of the character described including a series of horizontal tiers of independently movable individual yarn carriers, means for moving said yarn carriers along said tiers, releasable means connecting said carriers to said moving means, selective mechanism for operating said releasable means to successively release said carriers from said moving means as they move along said tiers, and manually operated means for operating the releasable means to permit interconnection engagement of the moving means with the released yarn carriers upon return of the moving means to a starting position.

50. In a machine of the character described including a series of horizontal tiers of independently movable individual yarn carriers, shafts for moving said yarn carriers along said tiers, means releasably securing said carriers to said shafts operable upon rotation of said shafts to successively release said yarn carriers therefrom, electrical means for selectively operating said shafts to release said yarn carriers and means for simultaneously rotating said shafts to permit interconnection engagement of the shafts with the released yarn carriers upon return of the shafts to a starting position.

51. A machine of the character described including a series of tracks, a series of individual yarn carriers movably mounted on said tracks, spring means carried by said carriers adapted to hold said carriers stationary on said tracks and releasable means for moving said yarn carriers along said tracks.

RALPH W. HOMAN.
